UNITED STATES PATENT OFFICE.

OTTO LEHMAN, OF NEW YORK, N. Y., ASSIGNOR, BY MESNE ASSIGNMENTS, TO THE STANDARD INCANDESCENT BURNER COMPANY, OF PORTLAND, MAINE.

INCANDESCENT-LAMP BURNER.

SPECIFICATION forming part of Letters Patent No. 653,254, dated July 10, 1900.

Application filed November 15, 1899. Serial No. 737,079. (No model.)

To all whom it may concern:

Be it known that I, OTTO LEHMAN, a citizen of the United States, residing at New York, in the county of New York and State of New York, have invented certain new and useful Improvements in Incandescent-Lamp Burners, of which the following is a specification, reference being had therein to the accompanying drawings.

- 10 My invention relates to that class of burners adapted to produce from a liquid hydrocarbon a flame suitable for heating to incandescence a filamentary or gauze mantle for incandescent illumination; and the invention has for its object to produce a burner of this kind adapted to be applied to well-known forms of kerosene or other liquid-hydrocarbon lamps, the improved burner being of such a character that there will be no offensive odor 20 or smell resulting from imperfect combustion when the lamp is first lighted, when it is burning, or after it has been extinguished. Means are also provided in the improved burner for avoiding smoking of the filamentary mantle, 25 such means serving to keep the burning end of the wick smooth and even, so that there will be no projecting filaments which will result in an uneven flame.

In the accompanying drawings, Figures 1 and 2 are central vertical sections at right angles to each other of the improved burner. Fig. 3 is a side view of the same; Fig. 4, a cross-section on line $x-x$ of Fig. 3. Fig. 5 is a detail view of a vertically-adjustable wick-controlling sleeve. Fig. 6 is a detail view of the mantle-support.

The base a of the burner is preferably provided with a screw-threaded portion b for attachment to the threaded collar of a lamp. 40 The said base a is also preferably provided with a screw-threaded portion c to receive a threaded portion d of a foraminous or open-work casing e , within the upper part of which is loosely fitted a skeleton or open-work sleeve f , which is attached to the chimney-gallery g , and which chimney-gallery supports the cone h .

The base a is preferably hollow, as shown, to form an air-heating chamber i , which communicates at one side of the burner by the

passage-way j with the interior of the draft-tube k , which is rigidly attached to the burner-base. The outer wall of the said chamber i is perforated for the free admission of air to said chamber, and as the burner-base is in 55 conductive connection with the top of the burner where the flame will be through the draft-tube k and wick-controlling tube n the said burner-base will become somewhat heated, so that the air entering the chamber i will 60 be heated on its way to the flame. This heating of the inflowing air contributes to more perfect combustion than would otherwise occur and makes a stronger blue flame than would be produced by using cold air, while 65 the inflowing outer cool air to the burner-base serves to prevent the said base from becoming too much heated.

Surrounding the draft-tube k is a sliding wick-raiser l , having at its upper end suitable 70 sharp-pointed projections to engage the wick m , which is wrapped around it and which is held against the points or projections of the wick-raiser by the wick-controlling tube n , having at its upper end an inturned lip o , 75 which projects above the outer portion of the upper end of the wick to about the middle of the thickness of the latter. The lip o may be integral with the tube n or formed on a ring 12, fixed to the top of said tube. The 80 lower enlarged part p of the said tube n embraces with a close sliding fit an annular flange q , projecting upward from the burner-base, the said part p of the said tube n being provided with bayonet-slots r , adapted to embrace pins or studs s on the said flange q . This construction permits the tube n to be removed when desired and also permits, owing to the heights of the inner parts of the bayonet-joint slots, a limited upward and 85 downward movement of the said tube relative to the burner-base.

Movable in a suitable guideway formed in the present instance by a small tube t within the draft-tube k is a rack u , attached at its 90 lower end to the wick-raiser, and which rack meshes with a pinion v , fixed to the wick-raising shaft w , provided with a suitable finger-wheel x for raising and lowering the wick.

Supported in the upper part of the draft- 95 100

tube *k*, as by a small spider *y*, is a cap *z*, attached to the upper end of a stem *2*, the said cap having a diameter somewhat less than the diameter in the opening at the upper end of 5 the cone *h*, and the said cap being preferably so arranged that it is slightly above the top of the said cone. This arrangement of the said cap relative to said cone affords the best possible results in heating the incandescent 10 filamentary mantle.

The sleeve *f*, depending from the chimney-gallery *g*, is provided with spiral slots *3*, having short, straight, or horizontal portions *4* at their lower ends, the said slots being engaged by pins *5*, attached to the outer open-work casing *e*. This construction permits the chimney-gallery to be raised by an upward and slight turning movement when the wick is to be lighted through lighting-openings *6* 15 in the open-work sleeve *f*, while the straight portions *4* at the lower ends of the spiral slots *3* permit the sleeve *f*, which supports the chimney-gallery, to be held in a raised position without danger of displacement when 20 the said sleeve and chimney-gallery have been lifted to light the wick. The spiral slots *3* prevent a too-sudden descent of the chimney-gallery when the latter is to be lowered, and thereby avoid danger of injury to the fragile 25 filamentary mantle, supported by and vertically movable with the chimney-gallery, by sudden jars which might otherwise occur when the chimney-gallery is lowered after the lamp has been lighted.

30 The incandescent filamentary mantle *7* is supported by a rod *8*, preferably fixed to an open-work sleeve *9*, fitting somewhat closely around the base of the cone *h*, but loosely encircling the top of said cone, so that the skirt 35 of the mantle may fall down between the said cone and the said sleeve, the mantle being thus steadied and held securely in place. The openings in the sleeve *9* permit of an inflow of air at the base of the mantle. The 40 sleeve *9* rests on the base of the cone *h*, and the latter serves as a stop when the mantle-holder is set in place to insure the proper adjustment of the mantle relative to the burner, so that no skill or attention on the 45 part of the user is required to secure this very important adjustment, the parts being suitably proportioned in their manufacture.

50 When the lamp is in operation after having been lighted, air flows freely from the chamber *i* in the base of the burner through the draft-tube *k* to the top of the interior portion of the wick *m* and at which top interior portion the combustion mostly occurs. Air will also flow freely through the open-work casing 55 *e* and open-work sleeve *f* to the interior of the chimney-gallery, where is formed at the upper end of the sleeve *f* a somewhat abrupt concave shoulder *11*, which tends to compress the upwardly-flowing air inwardly, and thus 60 by contracting the volume of air serves to increase the upward draft within the cone *h*.

In adjusting the wick to burning position

the latter is lifted by the wick-raiser until it comes in contact with the inwardly-turned lip or flange *o* at the upper end of the wick-controlling tube *n*, when a further upward movement of the wick will raise the said tube until its upward movement is arrested by the contact of the lower walls of the inner portions of the bayonet-joint slots *r* with the pins 70 or studs *s* on the flange *q* of the burner-base. The contact of the upper end of the wick with the said inwardly-turned lip of the wick-controlling tube evens the upper end of the wick, and if there are any projecting filaments which might cause an uneven flame such projecting filaments are smoothed down by contact of the wick with the said lip. When the wick in the position referred to is lighted, the proper adjustment of the wick 80 to burning position is effected by lowering the wick, and with it the wick-controlling tube *n*, (between which latter and the wick there is sufficient frictional hold to effect this result,) until the upper walls of the inner portions of 85 the bayonet-joint slots *r* come in contact with the studs *s*, and thereby arrest the further downward movement of the wick-controlling tube. A very slight further downward movement of the wick, so that its upper end is 90 just below the inturned lip or flange *o* of the wick-controlling tube, brings the said wick into what will ordinarily be proper burning position. Thus the wick is controlled and adjusted in a reliable manner, and, owing to 95 the proper adjustment of the wick and the peculiar construction of the coöperating parts of the burner, it results that a blue flame suitable for heating the filamentary mantle to incandescence is produced and a beautiful 100 white incandescence of the mantle is secured without danger of smoking the mantle, and the combustion is so complete that there is no offensive smell or odor when the lamp is first lighted, when it is burning, or after it 105 has been extinguished, the gasifying of the liquid hydrocarbon being produced at or so close to the point of combustion that there is no unconsumed gas which in escaping might produce an unpleasant odor when the lamp 110 has been extinguished.

Having thus described my invention, I claim and desire to secure by Letters Patent—

1. In a burner, the combination with the base thereof, provided with an air-heating chamber, of a draft-tube with which said chamber communicates, a vertically-movable wick-tube outside of said draft-tube and between which latter and said draft-tube the wick is received, and which tightly encircles 120 said wick, a wick-adjusting device also between said draft-tube and wick-tube, a vertically-movable chimney-gallery support, a cone sustained by said support, and means for holding an incandescent mantle above the 125 said cone.

2. In a burner, the combination with the base thereof, provided with an air-heating chamber, of a draft-tube with which said

chamber communicates, a vertically-movable wick-tube outside of said draft-tube and between which latter and said draft-tube the wick is received, and which tightly encircles 5 said wick, said wick-tube having an inturned lip at its upper end, a wick-adjusting device also between said draft-tube and wick-tube, a vertically-movable chimney-gallery support, a cone sustained by said support, and 10 means for holding an incandescent mantle above the said cone.

3. In a burner, the combination with the base thereof, a casing attached to said base, a vertically-movable chimney-gallery mounted 15 on said casing, a cone supported by said chimney-gallery, draft and wick tubes with means for holding a wick between them, and a mantle-holder consisting of a sleeve provided with a mantle-supporting rod, said sleeve loosely 20 surrounding the top of said cone with a space between these parts to receive the skirt of the mantle, the base of said cone serving as a stop for insuring the proper vertical adjustment of said sleeve.

25 4. In a burner, the combination with the base thereof, a casing attached to said base, a vertically-movable chimney-gallery mounted on said casing, a cone supported by said chimney-gallery, draft and wick tubes with means 30 for holding a wick between them, and a mantle-holder consisting of an open-work sleeve provided with a mantle-supporting rod, said sleeve loosely surrounding the top of said cone with a space between these parts to receive the skirt of the mantle, the base of said cone serving as a stop for insuring the proper vertical adjustment of said sleeve.

35 5. In a burner, the combination with the base thereof, of a draft-tube fixed to said base, 40 a wick-controlling tube loosely surrounding said draft-tube with space between said tubes for the reception of a wick, said wick-controlling tube tightly encircling said wick so as to be moved up and down thereby and being vertically movable relative to said base and being provided at its upper end with an inturned

lip, a casing attached to said base, a chimney-gallery supported by said casing and provided with a cone, and a cap supported by the said draft-tube and arranged centrally in the opening of said cone and slightly above the top of the latter. 50

6. In a burner, the combination with the base thereof, of a draft-tube fixed to said base, a vertically-movable wick-controlling tube 55 loosely surrounding said draft-tube with space between said tubes for the reception of a wick, said wick-controlling tube tightly encircling said wick so as to be moved vertically therewith and having at its upper end an in-turned lip and being provided at its lower portion with bayonet-joint slots, and the said burner-base being provided with an upwardly-projecting flange having pins engaging said slots, a casing attached to said base, 60 a chimney-gallery supported by said casing and provided with a cone, and a mantle-holder supported by said chimney-gallery. 65

7. In a burner, the combination with the base thereof, of a draft-tube fixed to said base, 70 a wick-controlling tube loosely surrounding said draft-tube with space between said tubes for the reception of a wick which said wick-tube tightly encircles so as to be moved vertically therewith, an outer casing attached to 75 said base, a vertically-movable chimney-gallery provided with a depending sleeve inclosed by said outer casing, said depending sleeve having at its interior upper portion an abrupt shoulder forming a contracted opening at the top of said sleeve, a cone supported by said chimney-gallery and the central opening of which communicates with the said contracted opening of said depending sleeve, and 80 a filamentary mantle surmounting said cone. 85

In testimony whereof I affix my signature in the presence of two witnesses.
